DANGER CALL ALARM

Cecil Carlton Parker, Hyde Park, N. Y.

Application July 10, 1943, Serial No. 494,437

3 Claims. (Cl. 116—67)

The invention herein disclosed relates to alarms and the objects of the invention are to provide a device of this nature, which may be readily held concealed in the hand and be operated in the event of bodily attack or danger of any character, to send out a distress signal.

Further objects are to provide such a device which will be of simple, inexpensive, light construction, easily carried in a pocket or pocket-book and which will be readily chargeable or renewable to supply the energy required for sending out a recognizable distress call for an appreciable length of time.

Other desirable objects will appear as the specification proceeds.

The drawing accompanying and forming part of the following specification illustrates a present practical embodiment of the invention. Structure however may be modified and changed within the true intent of the invention as will become apparent from the actual scope of the invention as hereinafter defined and claimed.

Fig. 1 in the drawing is a longitudinal sectional view of a form of the invention charged and ready for use.

Fig. 2 is a broken sectional view showing the trigger actuated to effect the sounding of the alarm.

Fig. 3 is an end view of the device.

Figs. 4 and 5 are end views of the device as appearing in Figs. 1 and 2 respectively.

A special feature of the invention is the utilization of a small compressed gas cartridge for supplying the energy for sounding the alarm.

In the drawing, a gas cartridge or capsule of typical design is illustrated at 5, having a puncturable seal 6, at one end.

This cartridge is seated within a casing carrying a sounding device, or otherwise connected with the sounding means and a hand trigger, or other suitable member for effecting puncture of the cartridge seal.

In the illustration, the cartridge is shown seated in a small cylindrical gastight casing 7, having a removable screw cap 8, at one end.

The sounding device is shown as a whistle 9, supported by the cover directly over the seal end of the cartridge.

The seal puncturing means is shown as a hand actuated trigger lever 10, pivoted on the cover at 11, and carrying a point 12, projecting through the center opening 13, in the whistle, into position for engagement with the seal.

The trigger lever 10, is shown as of angled formation, providing a short base portion 14,

extending across the cap and carrying the puncturing point and a longer leverage handle portion 15, extending along the side of the casing in position for grasping and applying a squeezing pressure.

The construction as disclosed is small enough for being held concealed in the palm of the hand, with the fingers about the lever and ready to actuate the same by a slight squeezing movement. Once the seal is broken, the whistle will continue to sound even though the device be dropped or knocked out of the hand. These small gas containers hold enough compressed carbon dioxide or other gas to keep the whistle sounding for a long enough time to be heard and recognized as a distress call by anyone within reach of the sound. The whistle may be of the police type, so that the signal will be recognized as a call for police assistance.

The cartridges are easily replaceable upon simply unscrewing the cap, this enabling the spent cartridge to be dropped out and a new one to be inserted in its place.

Instead of requiring the gripping power of the fingers to break the seal, the power for this purpose may be provided by a spring strong enough to actuate the puncturing point and arranged to be released by the trigger lever.

The gas compressed in the small flasks or cartridges such as illustrated, provides a practical energy source for operating the alarm.

In the present illustration, the whistle is detachably held by the cap, this construction having the advantage of enabling the ready substitution of different kinds or tones of whistles.

A suitable guard or safety lock may be provided to prevent accidental discharge, such as the spring clasp shown at 16, attached to the handle and shouldered at 17, to normally hold the handle away from the casing as in Fig. 4, but arranged with sufficient pressure to yield as in Fig. 5, and thereupon to clasp itself about the casing and hold the trigger in the actuated position. Held in this relation, the handle indicates that the cartridge has been discharged and that the device should be refilled.

While generally considered as a danger call alarm and so entitled in this disclosure, it will be realized that the invention is not restricted to this particular use.

As a further protective means, the casing or holder for the gas cartridge may have a rear-view mirror 18, on the side of the same, adjacent but out of the way of the handle 15, for enabling a party suspecting danger to see to the

rear or to the side, while getting ready to set off the alarm.

The mirror may be an integral portion of the casing if the latter be of a light reflecting material or have a light reflective surface. Otherwise, the mirror may be a separate piece attached to the side of the casing.

What is claimed is:

1. In combination, a gas-tight casing for housing and adapted to be opened to receive a sealed cartridge of compressed gas and provided with a vent for escape of gas released from said cartridge, a hand operable trigger on said casing for rupturing the seal of said cartridge, said vent including a whistle having a passage therethrough and said seal rupturing means including a puncture point extending through said opening in said whistle.

2. A danger call alarm, comprising a small generally cylindrical compressed gas cartridge having a puncturable seal at one end, a small substantially cylindrical hand-size container operable to receive said cartridge, and in which said cartridge is sealed, a whistle mounted in one end of said container in line with the puncturable seal of the cartridge, a hand lever closely overlying said container, a seal puncturing point operable by said lever and projecting into the

end of the casing in position for engagement with the cartridge seal and hand pressure yielding means for normally retaining the hand lever in non-puncturing position.

5 3. A unitary danger call alarm to be carried concealed in the palm of the hand and be actuated by the fingers gripping the same, said alarm comprising a small compressed gas cylinder having a puncturable seal at one end, a small cylindrical container of a size to closely receive said compressed gas cylinder and having readily releasable means for removably securing said cylinder therein, said container being open at one end and having an alarm sounding whistle 10 at said open end and exposed to pressure of gas released from the compressed gas cylinder, a puncturing point within the container opposed to the seal of the gas cylinder, a lever pivotally supported at one end of the container and extending along one side of the container for actuation by the fingers of the hand in which the device is gripped and means operable by said lever for effecting the coaction of said puncturing point with the seal of said compressed gas cylinder and whereby said alarm may be sounded 15 by a simple squeezing action of the hand in which the device is carried and concealed.
